UNITED STATES PATENT OFFICE.

AARON K. KLINE, OF SOMERVILLE, NEW JERSEY.

CAR-BRAKE.

SPECIFICATION forming part of Letters Patent No. 284,293, dated November 9, 1880.

Application filed May 31, 1880. (No model.)

To all whom it may concern:

Be it known that I, AARON K. KLINE, a citizen of the United States, residing at Somerville, in the county of Somerset and State of New Jersey, have invented new and useful Improvements in Car-Brakes, of which the following is a specification.

This invention relates to an improvement in car-brakes; and it consists of the combination 10 of a push-bar extending throughout the length of the car, a lever pivoted to the car-frame and connected to the push-bar, a slide fitted in guides on the car-frame and engaging with said lever, mechanism, substantially as herein- 15 after described, for connecting the slide with the brake-heads, and two springs placed on said slide, said springs serving to equalize the pressure throughout the train and prevent breaking, as also to take off the brakes, as 20 hereinafter more fully set forth.

This invention is illustrated in the accompanying drawings, in which—

Figure 1 is an inverted plan view. Fig. 2 is a vertical longitudinal section.

25 Similar letters indicate corresponding parts. In the drawings, the letter A designates the platform of a car running on wheels B B. The under side of the platform A is provided with a push-bar, a a, sliding longitudinally in bearings or guides b b. This push-bar is intended to abut with its end against the end of a corresponding push-bar on the car in front, and thus a continuous line is produced, reaching to the locomotive.

35 The locomotive is provided with a steam-piston or other arrangement, preferably under the engineer's control, which communicates motion to the push-bar a a, pressing it, for example, in the direction of the arrow 1, shown 40 thereon.

To the car-frame is pivoted a lever, c, swinging about the pivot d. The other end of the lever c is fastened to the push-bar a, and when the push-bar is pressed in the direction of arrow 45 1 the inner end of the lever c swings along with it. Of course, in order to allow free motion and prevent breaking, it is necessary to make the lever c in two parts, as shown in the drawings, which parts are connected by a pivot, 50 g, fastened to one division of the lever c, and

playing in a slot in the other division. This motion of the lever c is, by means of lugs e e, communicated to the slide f, also on the under side of the platform A, and sliding in bearings or guides h. On the slide f is an arm, i, extending therefrom and sliding on the same. Springs j j hold the arm i in position and communicate the motion of the slide f to the arm i. The arm i is connected by a chain, k, or otherwise to the lever l, having its fulcrum o on the swinging beam p, which carries the brake-heads, and when said chain k is pulled by the arm i in the direction of arrow 1 it presses the brake-heads q against the wheels B by means of said chain k and lever l. To the other end 60 of the lever l is fastened a rod or chain, C, by which the motion of said lever l is communicated to the lever n, and by it to the beam p' and brake-head q'. When the push-bar a is pressed in the direction opposite to that of 65 arrow 1, the arm i communicates its motion to the chain m and lever n, producing a like result as before. The beams p p' swing freely to and fro in arms or rods s depending from the body of the car, as is usual in the arrangement of brakes.

In order that the pressure on all the brakes in the train may be equalized, the arm i is not rigidly attached to the slide f, but rests loosely thereon, and is only prevented from sliding by 80 the springs j j. As these springs j are made of nearly equal strength throughout the whole train, the pressure of all the brakes on the wheels will be nearly equal. Said springs j also prevent a too great strain from being 85 brought on the chains k m, thus removing all liability of breaking of these chains or any other part of the mechanism.

When the pressure on the push-bar a is released, the spring j on the other side of the 90 arm i pushes the arm i and the slide f, as well as the push-bar a, back to their original position. In order to insure contact of the ends of the bar a, I provide the same with broad heads, as shown. In case the push-bar a 95 should be dispensed with, the contact can be established between the slides f. Of course, as these slides are not in the center of the cars, the distance between the ends of these slides would be shortened or lengthened whenever 100

the cars pass a curve. To allow for this the slides *f* are allowed somewhat greater play. I also provide buffers or dead-woods *rr*, which abut against each other in passing a curve, so as to avoid accidental contact of the slides *f*. In coal-cars the bottoms of which swing down to deposit the coal, the bar *a* would be in the way. In order to obviate this I make the bar *a* in two short divisions, one at each end of the car, and connect these divisions by a quadrangular frame, consisting of metal or other stout rods, said frame being of about the same size as the platform of the car. This frame allows the coal to drop down within itself without hindering its passage. This frame may be connected to the slide *f* by a lever or chain; but in this arrangement I prefer to dispense with the slide *f* and attach the arm *i* directly to this frame. By this arrangement I obtain the benefit of the arrangement of the springs *j*, at the same time preventing the coals

from falling on any of the operating parts of the device and avoiding injury to the same.

What I claim as new, and desire to secure by Letters Patent, is—

The combination, in a car-brake, of a push-bar extending throughout the length of the car, a lever pivoted to the car-frame and connected to the push-bar, a slide fitted in guides on the car-frame and engaging with said lever, mechanism substantially as described for connecting the slide with the brake-heads, and two springs placed on said slide, all constructed to operate substantially in the manner shown and described.

In testimony whereof I have hereunto set my hand and seal in the presence of two subscribing witnesses.

AARON K. KLINE. [L. S.]
